GARMENT HANGER

Haimi Navon, Brooklyn, N. Y.

Application February 12, 1946, Serial No. 646,992

5 Claims. (Cl. 223—98)

1

This invention relates to garment hangers, and aims to provide a novel, practical and efficient hanger having means to prevent slipping of the garment from the hanger together with a shield to keep dust from settling on the garment.

Standard forms of garment hangers and separate shields are in common use, but these possess inherent disadvantages which are especially noticeable and important in shops or stores where dresses are shown many times during business hours, as it is very difficult to keep the dresses covered with shields because of lack of time. The hanger of this invention overcomes this difficulty in that the shield covers the dress automatically after the dress is slipped on to the hanger, thus keeping the dress protected from dust and light at all times.

In the case of ordinary hangers, many dresses, because they are cut with wide neck lines, slip off the hanger on to the floor, and this presents a perplexing problem in many dress shops. This invention provides means for automatically retaining the garment on the hanger at all times.

The above general as well as additional and more specific objects will become apparent in the following description, wherein characters of reference refer to like-numbered parts in the accompanying drawings. It is to be noted that the drawings are intended for the purpose of illustration only, and that it is neither intended nor desired to limit the scope of the invention necessarily to any or all of the specific details of construction illustrated excepting insofar as they may be deemed essential to the invention.

Referring briefly to the invention,

Fig. 1 is a front elevational view of the combination hanger and shield, with parts of the shield broken away and partly in section.

Fig. 2 is a front elevational view of the same.

Fig. 3 is a view similar to Fig. 2, showing the combination hanger clamp arms or wings and shield members or sections, in turned up position where they are releasably retained while a garment is hung or removed from the hanger.

Fig. 4 is a plan view of the hanger with the shield omitted.

Fig. 5 is a plan view of the right-hand half of the hanger of Fig. 4, with its shield member in place thereon, the latter being partly broken away and partly in section.

Fig. 6 is a fragmentary sectional view taken on the line 6—6 of Fig. 4.

Fig. 7 is a perspective view of one of the two complementary shield sections which are removably mounted on the hanger clamp arms.

Fig. 8 is a plan view, partly broken away and partly in section, similar to Fig. 4, showing a modified form of construction of the hanger clamp arms.

Fig. 9 is an enlarged fragmentary plan view

2

of the hanger of Fig. 8, with parts broken away and partly in section.

Fig. 10 is an enlarged fragmentary plan view of another portion of the hanger of Fig. 8.

Fig. 11 is an enlarged fragmentary plan view, with parts broken away and partly in section, of the lateral extending means of Fig. 10.

Referring in detail to the drawings, the numeral 10 indicates a common form of garment hanger, having a center bolt 11 terminating at the top in a hook 12. A plate or the like 13, arched to conform to the curvature of the hanger 10, is secured by screws or other means to the top of the hanger 10 intermediate the length of the hanger and provided with a central opening or hole through which the bolt 11 passes, shown at 14. At each end of the plate 13, the plate is provided with substantially upright laterally spaced extensions 15, and at its upper edge each upright 15 has formed thereon a pivot or hinge ear 16, or sleeve, the two sleeves 16 at each end of the plate being in axial alignment.

Clamp arms 17 and 18 are provided as follows,

each arm being formed of a single length of wire or the like bent into the desired shape. The arm 18 is thus bent into the shape shown in Figs. 1 and 4, comprising the two side lengths of members 19, the end member, rounded, 20, and the other end which comprises a pair of spaced, par-

allel doubled-back fingers 21. The clamp arm 17 is similar in having the two sides 22, the outer end 23, and at the inner end a pair of doubled-back spaced parallel fingers 24. The length of wire extending from each finger 21 is further

deformed to pass in alignment through the respective sleeves 16 on the right side, as shown at 25, to provide pivot stub shafts in the sleeves, and after coming out of the sleeves in the space between the two aligned sleeves, the wire is fur-

ther shaped into an upturned loop 26. The arm 17 is formed in a like manner with respect to its hinge sleeves 16 and also terminates in a similar upturned hook 27. It is to be noted that the 21 and 24 possess a degree of resiliency, and this

is sufficient, when the arms are in the extended position of Fig. 1, to cause sufficient frictional engagement between each finger 21 and the adjacent finger 24 to releasably lock the two arms 17 and 18 in the said extended position. It is

obvious that pressure of the fingers against the hollows of the hooks 26 and 27 will cause the arms 17 and 18 to swing upward into the position shown in Fig. 3. If desired, any releasable catch means, not shown, may be provided like-

wise to releasably hold the two arms in the said upward position. Cross members 28 may be provided for lateral bracing of the arms.

Each arm 17 and 18 is adapted to have a shield of any desired fabric slipped thereover, one such

shield being shown at 29 in Fig. 7, and the other

shield 30 is substantially similar in construction and complementary thereto. Each shield comprises a pair of opposed side walls 31 and a curved top wall 32, thereby providing a compartment closed on all sides excepting the bottom and the inner end 33. The top 32 is formed of two spaced layers of material, 34 and 35, and a cut-out 36 is provided as shown. The shield 29 is slipped over the arm 18 by inserting the latter into the space between the layers 34 and 35 and drawing the shield upon the arm until it assumes the position shown in Fig. 1. In the latter position the sleeves 16 on that side assume the position shown in Figs. 1 and 2 with respect to the shield top 32, with the sides 38 of the cut-out 36 extending along the sides of the fingers 21 and 24, and the sleeves registering against the end 37 of the cut-out 36. Thus, the sides 31 of the shield 29 overlap the sides 31 of the shield 30 when they are both in position. Means, not shown, may also be provided to interlock the two assembled shields, although the frictional engagement of the arm sides 19, 22 with the shield top 32 is generally sufficient to retain the shields thereon. However, in the modification to be described below, an added engagement or force is provided which positively retains the shields on the clamp arms.

In Figs. 8-11, inclusive, a substantially similar but improved structure is shown for the shield supporting arms 17a and 18a. Those parts of these figures which are identical to like parts of the figures previously referred to, bear like reference numerals; and those parts of Figs. 8-11 which are equivalent to similar parts in Figs. 1-7, inclusive, bear the same reference numerals followed by the letter "a".

Both arms are formed of two bilaterally symmetrical halves 39 and 40, in such manner as to be equivalent to splitting the rounded ends 20a and 23a at 50, by making the cross-members 28a in two mutually telescopic parts, and likewise splitting the pivot stub shafts 25a to make each of the four of them in two aligned parts. In the case of each of the latter, a sleeve 39b is rigid at one end about one end of the broken shaft 25a, that is, the end 40b, and a second sleeve 42 which telescopes into the sleeve 39b, is rigid about the other end 41. Collars 43 on the opposed ends of the stub shafts 40b-41 have a coiled compression spring 48 therebetween, which normally urges the two shafts, and hence their respective sleeves, apart, as the collars are urged apart by this spring.

In the case of the cross-braces 28a, each is broken into two sections 44, and a sleeve 45 whose ends are closed except for aligned openings permitting the rods 44 to pass through slidably, loosely surrounds the ends of these shafts, which are also provided with rigid collars 46 separated by a compression spring 47. It is apparent that the springs 47 and 48 normally urge the two half-sections 39-40 apart so that, when the shields are mounted thereon as previously set forth, the force of the sides of the arms 17a-18a against the folds of the roof 32 securely retains the shields on the arms.

The degree of lateral expansion permitted by the connecting means between the two sections 39 and 40 is of course limited by the limit stops provided, as described. Instead of a single limit stop at the extreme of the lateral expansion permitted, as shown, a series of longitudinally spaced friction stops could be provided between the two

movable parts so that their degree of lateral separation could be regulated releasably. This would, however, be an obvious expedient, and would play no role in the underlying invention.

When a garment is hung on the hanger 10, with the shields in the raised position shown in Fig. 3, the latter are swung down against the shoulders of the garments, so that the side and end walls of the shields protect the garment from dust and light, as is obvious from Fig. 2. Moreover, the pressure of the clamp arms 17 and 18 against the shoulders of the garment tend to clamp the garment to the hanger and thus to prevent its slipping from the hanger. The lateral expansion of the modified form permits widening of the arms 17 and 18 to accommodate men's clothing, or men's or women's coats, as well as to securely retain the shields thereon, which might otherwise also slip off. The shields are obviously easily removed for laundering, and as easily replaceable.

The hanger as set forth should prove of inestimable value and utility to dress shops and stores. Obviously, modifications in form and structure may be made without departing from the spirit and scope of the invention. Any suitable resilient means may be provided to urge the arms and shields normally into their lowermost positions against the hanger 10, and as an example of such means, coiled springs surrounding the stub shafts 25, not shown, may be cited.

I claim:

1. A device of the class described comprising a garment hanger, a member secured thereto intermediate the length of the hanger at the top of the latter, arms hingedly secured at one end to the ends of said member and extending outward in substantially the plane of the hanger, dust shields having pockets extending longitudinally in the roofs thereof, said shields having the entrances to said pockets juxtaposed and being slidably mounted on said arms with said arms registering in said pockets.

2. The device set forth in claim 1, each of said arms being formed of longitudinally split and bilaterally symmetrical complementary half sections, and resilient means joining said half-sections and normally urging the same apart, said sections having limit stops in association with said last-named means.

3. The device set forth in claim 1, said member comprising a plate having upstanding ends whereby the hinged connection between said arms and said ends of said member are spaced upward from said hanger.

4. The device set forth in claim 1, said arms having finger grip hooks rigid with their mutually adjacent ends.

5. The device set forth in claim 1, each of said arms being formed of longitudinally split and bilaterally symmetrical complementary half sections, aligned transverse rods extending from said half sections, said rods having compression springs mounted between their juxtaposed extremities thereby normally urging said aligned rods apart.
